CLAIM

The ornamental design for a light fixture, as shown and described.

DESCRIPTION

FIG. 1 is a bottom perspective view of a light fixture, showing my new design.

FIG. 2 is a front elevation view of the light fixture of FIG. 1, the rear elevation view being a mirror image of the front view.

FIG. 3 is a right side elevation view of the light fixture of FIG. 1, the left side elevation view being a mirror image of the right side view; and,

FIG. 4 is a bottom plan view of the light fixture of FIG. 1.

The broken lines illustrate portions of the light fixture which form no part of the claimed design.
